UNITED STATES PATENT OFFICE.

ROBERT L. ROCKWELL, OF SEATTLE, WASHINGTON, ASSIGNOR OF ONE-HALF TO F. R. FALLER, OF EVERETT, WASHINGTON.

ELECTRIC FURNACE.

Application filed May 26, 1924. Serial No. 715,854.

To all whom it may concern:

Be it known that I, ROBERT L. ROCKWELL, a citizen of the United States, and a resident of Seattle, King County, Washington, have ⁵ invented certain new and useful Improvements in Electric Furnaces, of which the following is a specification.

My invention relates to improvements in electric furnaces of the single phase type ¹⁰ and methods of operating the same, and is particularly applicable to such furnaces using comparatively small currents at the higher arc voltages.

It has been customary heretofore to operate ¹⁵ single phase electric furnaces on single phase feeders tapped from polyphase supply systems. This practice is objectionable because of the unbalancing effect of such loads, especially where the furnace load is a ²⁰ considerable percentage of the output capacity of the source of supply. For this reason it is desirable to derive the single phase current jointly from the several phases of the polyphase system. In the past, however, ²⁵ this has required considerable additional equipment of a special nature, the use of which is both expensive and objectionable.

The smaller sizes of single phase furnaces of the arc type usually require the use of ³⁰ auxiliary reactors in either the primary or secondary circuits of the furnace transformers in order to stabilize the furnace arcs and reduce the severe fluctuations in load incident to their operation, even when the ³⁵ furnace transformers are specially constructed with "built-in" reactance. For this reason where a polyphase electric furnace is supplied by a bank of two transformers or their equivalent and it is desired to operate ⁴⁰ a small single phase furnace when the polyphase furnace is not in use, one of the transformers, an auxiliary reactor and suitable switches have previously been used to that end. It is evident that the auxiliary reactor ⁴⁵ is an additional item of expense and is used only when the small furnace is in operation.

The object of my invention is to provide improved means whereby electric furnaces may be supplied with single phase electric ⁵⁰ energy derived jointly from the several phases of polyphase alternating current systems.

A further object is to provide a method of

operating single phase electric furnaces without the usual auxiliary reactors by using the impedances of a plurality of transformers in combination with the several phases of a polyphase source to stabilize the arc. ⁵⁵

In the accompanying drawings I have ⁶⁰ illustrated diagrammatically several embodiments of the invention.

Figure 1 is a diagrammatic illustration of one form of the invention for use in connection with two phase supply leads from a ⁶⁵ polyphase source, and Figure 2 is a simplified diagram of the electrical connections showing the phase relation.

Figure 3 is a similar illustration of another form of the invention for use in connection with three phase supply leads from a polyphase source. ⁷⁰

Figure 4 is a vector diagram showing the secondary circuit voltage and current relations; the inductive reactance of the ⁷⁵ transformers and supply leads being neglected.

Figure 5 is a diagram of connections of an adaptation of the invention for the operation of a single phase furnace in conjunction with a larger two phase furnace. ⁸⁰

Like reference numerals are used to indicate like parts throughout the drawings.

Referring particularly to the form of the invention illustrated in Figure 1, a single phase electric furnace of the arc type ⁸⁵ having an upper movable electrode 2 and a lower fixed electrode 3 is shown in series circuit combination with the secondary windings 4 and 5, of a pair of transformers 6 and 7, respectively, by means of suitable connection conductors 8, 9 and 10.

A quadrature time phase relation between the two electromotive forces 11 and 12 induced in secondary windings 4 and 5, as indicated in Figures 2 and 4, is obtained ⁹⁵ by connecting primary winding 13 of transformer 6 to one phase 14—14 and primary winding 15 of transformer 7 to the second phase 16—16 of suitable two phase supply leads or bus bars. ¹⁰⁰

Since the transformer secondaries 4 and 5 are in series with each other and with the furnace electrodes, their electromotive forces 11 and 12 combine to form a resultant electrical pressure 17 which is effective in forcing ¹⁰⁵ single phase current 18 through the

furnace arc 19. It is evident that the furnace current 18 is carried by each of the transformer secondaries 4 and 5 and in turn is made proportionately common to the two phase S of the polyphase source (not shown) by means of transformers 6 and 7 and supply leads 14-14 and 16-16.

In Figure 3 is shown another form of the invention, wherein the polyphase supply leads 20, 21 and 22 deliver three phase alternating current to primary windings 13 and 15 by means of the well known T connection of these windings to the supply leads. It will be noted that the secondary, or arc circuit, connections are identical to those of Figure 1, and that in this case electromotive forces 11 and 12 induced in the L connected secondary windings 4 and 5 are likewise in quadrature time phase relation to each other and hence combine to form a resultant electric pressure that forces single phase current through the furnace arc, as illustrated in Figure 4, and previously explained. Furthermore it will be apparent to those skilled in the art that this single phase current is likewise made proportionately common to each of the three phases of the polyphase source (not shown) by means of the T connection of primaries 13 and 15 of transformers 6 and 7, which is one object of the invention.

Referring particularly to Figure 4, it is understood and expected that the phase relation between the secondary electromotive forces 11 and 12 may differ more or less than ninety electrical degrees, as shown, depending on the power factor of the furnace load and the electrical characteristics of the transformers and other parts. It is also understood that electromotive forces 11 and 12 may or may not be equal for similar reasons, or in case transformers of different secondary pressure are used.

The satisfactory operation of an electric arc furnace in connection with a constant potential source of supply requires that the total impedance of all parts of the circuits between the source and furnace arc shall be sufficient to properly limit the flow of current for the various values of arc resistance within the operating range of the furnace.

Impedance is made up of both resistance and reactance, but the economic operation of electric furnaces demands that the resistance values be kept within reasonable limits. The secondary or arc circuit, consisting of arc 19, electrodes 2 and 3, and connecting conductors 8, 9 and 10, together with the polyphase supply leads, contribute only a small part of the total impedance needed for arc stabilization for furnaces using comparatively small currents at the higher arc voltages. By use of my invention and taking advantage of the inherent reactances of both

mutual inductance of their primary and secondary windings, I find I not only can supply the furnace with single phase alternating current derived jointly from the several phases of a polyphase source, but I can also secure excellent arc stabilization for the operation of the furnace over a wide range of current values without the use of auxiliary reactors.

An important application of the invention wherein advantage is taken of both of these features, is illustrated diagrammatically in Figure 5. In this case the polyphase supply leads 20, 21 and 22 are used to energize the primary windings 13 and 15 of transformers 6 and 7 as previously described.

With the three-pole double-throw transfer switch 23 in the position shown by full lines and the quadrature or two-phase relation between secondary electromotive forces 11 and 12, two phase current is supplied the large polyphase furnace 24 having two movable upper electrodes 2' and 2'', and fixed lower electrodes 3' which are connected to transformer secondary windings 4 and 5 by means of conductors 9', 10', 25, 26, 27 and 27' as clearly illustrated in the diagram.

Obviously secondary winding 4 supplies single phase current to arc 19' in quadrature time phase relation to the single phase current supplied to arc 19'' by secondary winding 5. Lower electrode 3', conductors 27 and 27' and the center blade of transfer switch 23, act as a common return for these two arc currents.

It is assumed that the inherent impedances of transformers 6 and 7 together with the impedances of their connecting circuits are sufficient for arc stabilization for the high current values at which arcs 19' and 19'' would be operated.

My invention may be used for the operation of the small single phase furnace 1 when the polyphase furnace is not in use, by placing the transfer switch 23 in the position indicated by the dotted lines. This provides a series circuit combination of transformer secondaries 4 and 5, furnace electrodes 2 and 3, and arc 19 by means of connecting conductors 8, 9', 9'', 10', and 10'', and the two outer blades of switch 23. The two electromotive forces induced in secondary windings 4 and 5 will now combine to form a resultant electrical pressure which is effective in forcing single phase current through arc 19, as hereinbefore explained, instead of supplying two phase current to the two arcs in the polyphase furnace 24. Furthermore, I find that arc 19 of furnace 1 may now be operated with excellent stabilization over a much lower range of current values than was possible for either arc of the polyphase furnace, and without the use of auxiliary reactors.

My invention is not necessarily limited to

the details shown and described in these specifications, as the invention may be embodied in various other forms. For example, there are a number of equivalent transformer combinations that may be substituted for the two transformers I prefer to use as illustrated in the accompanying diagrams. One of these is the substitution of a polyphase transformer for the two single phase 10 transformers. Another is the use of so-called auto-transformers wherein the primary and secondary windings are not electrically independent, as shown, for the transformers in my diagrams. It will be understood also that the single phase electric furnace is illustrated only diagrammatically and that any type of single phase electric furnace may be used. For instance, instead of one movable upper electrode and a single 20 fixed lower electrode, as in my diagrams, the furnace may have two movable upper electrodes which may provide either one or two arcs, depending on the type of furnace used.

Various other changes may be made from 25 what I have disclosed herein without departing from the spirit of the invention which I have set forth in the appended claims as new and desire to secure by Letters-Patent of the United States.

30 Having thus described my invention, what I claim is:

1. The combination of an electric furnace, a plurality of transformers energized by polyphase alternating current and having substantially a quadrature time phase relation between their respective secondary electromotive forces, and means for connecting the secondaries of said transformers in series circuit combination with the electrodes 40 of said furnace.

2. The combination of polyphase alternating current supply leads, means for using the several phases of the same to provide a quadrature time phase relation between two electromotive forces, means of connecting the sources of said electromotive forces in series circuit combination with the electrodes of an electric furnace whereby said electromotive forces combine to form a resultant 50 electrical pressure that is effective in forcing single phase current through said furnace.

3. The combination of a single phase, electric furnace, a plurality of transformers, polyphase alternating current supply leads, means of connecting the same to the primaries of said transformers to produce a nominal quadrature phase relation between their respective secondary voltages and means for connecting the secondaries of said 60 transformers in series with each other and to the electrodes of said furnace.

4. The combination with a single phase electric furnace, of two transformers whose secondaries are connected in series to the 65 electrodes of said furnace and whose pri-

maries are energized, respectively, by the two phase of a two-phase source of alternating current.

5. The combination with a single phase electric furnace of two transformers having 70 their primaries T connected to three phase supply leads, and having their secondaries connected in series with each other and with the electrodes of said furnace.

6. An electric arc furnace in combination 75 with a plurality of transformers with built-in reactance, polyphase alternating current supply leads, means of so connecting the same to the primaries of said transformers as to provide a nominal two-phase relation between their secondary voltages, means of L 80 connecting the secondaries of said transformers, and means of connecting the ends of said L to the electrodes of said furnace, whereby the same may be supplied with 85 single phase alternating current.

7. An electric arc furnace having a single movable upper electrode and a single fixed lower electrode, in combination with two 90 transformers with built-in reactance, polyphase alternating current supply leads, means of connecting said supply leads to the primaries of said transformers to provide substantially a two-phase relation between their secondary voltages, means of L connecting the secondaries of said transformers and means of connecting the remaining terminals of said secondaries to the upper and lower electrodes respectively of said furnace. 95

8. In combination, a single phase electric 100 furnace, a plurality of transformers, polyphase alternating current supply leads, means of connecting the same to the primaries of said transformers to produce substantially a two-phase relation between their secondary voltages, means for L connecting the secondaries of said transformers, switching means and suitable conductors whereby the ends of said L may be connected in series 105 circuit combination with the electrodes of said single phase furnace, or whereby the ends and junction of said L may be connected to the electrodes of a two-phase furnace. 110

9. The method of supplying single phase electric energy to an electric furnace which 115 consists of combining the several phases of a polyphase source of alternating current and a plurality of transformers by connecting the same to said source and to said furnace so as to provide a quadrature phase relation between two electric pressures that combine to produce a resultant electric pressure effective in forcing single phase current through said furnace. 120

10. The method of operating an electric 125 furnace arc with single phase electric energy derived jointly from the several phases of a polyphase source of alternating current which consists of using said polyphase source and suitable means to provide a quad- 130

rature time phase relation between two electrical pressures which combine to form a resultant pressure to force single phase current through said arc.

5 11. The method of operating single phase electric furnaces which consists in stabilizing the arc by means of combining the impedances of a plurality of transformers

whose secondaries are in series circuit combination with said arc, and whose primaries 10 are energized jointly by the several phases of a polyphase source of alternating current.

Signed at Seattle, King County, Washington, this 1st day of May 1924.

ROBERT L. ROCKWELL.
